LEATHER SOLE CHANNELING AND STITCHING MACHINE

Herbert Corral, Helensburgh, and James Heggie, Clydebank, Scotland, assignors to The Singer Manufacturing Company, Elizabeth, N. J., a corporation of New Jersey

Application June 23, 1934, Serial No. 732,030
In Great Britain June 28, 1933

9 Claims. (Cl. 112—45)

This invention relates to sewing machines, particularly for stitching soles of footwear, comprising a leather ply and a felt ply, and aims to provide an improved construction for channeling the leather ply and stitching in the same operation.

In the machine according to the invention the channeling is effected by a stationary knife which engages the leather ply of the sole, the leather ply being located uppermost and the felt ply overlying the throat plate so as to be engageable by the feed dog.

The sole of the presser foot conveniently comprises interconnected sections serving to clamp between them a fixed channeling knife blade located immediately in front of the needle aperture in the presser foot. The rear face of the knife blade is concaved so as to afford a guide for the needle which is thus guided close to the point of cut. The knife blade is of arcuate form and adjustable in the vertical plane containing the line of cut.

For feeding the work there is employed, in addition to under feeding mechanism including a feed dog, an upper feeding element constituted by a feed slide carried by the presser foot and operatively connected to the usual lower feed rock shaft, whereby the feed slide is reciprocated parallel to the plane of the work in contact with antifriction bearing members received in a raceway in the under side of the presser foot.

With the described arrangement there is no tendency to drag the felt ply away from the leather ply, and even and clean cutting by the knife is effected.

In the accompanying drawings Figs. 1—3 show the upper and lower feeding mechanisms, of a sewing machine embodying the present invention, Fig. 1 being an elevation in a plane parallel to the line of feed, Fig. 2 a part plan part horizontal section on the line *a—a* of Fig. 1, and Fig. 3 a part front elevation part vertical section on the line *b—b* of Fig. 1; Fig. 4 is a fragmentary plan, part horizontal section, showing the throat plate, the feed slide, the feed dog, and the channeling knife; Figs. 5—9 are detail views of the knife blade, Fig. 5 being a side elevation, Fig. 6 an elevation viewed in the direction of feed, Fig. 7 an elevation viewed in the opposite direction, Fig. 8 an enlarged horizontal section on the line *c—c* of Fig. 5, and Fig. 9 an inverted plan view of the lower or operative end of the blade.

Referring to the drawings, 1 denotes the head of the sewing machine bracket arm in which are journalled the reciprocating needle-bar 2 and the usual spring-depressed presser-bar 3, said presser-bar being adapted to be lifted by manual operation of the lifter lever 3'. 4 denotes the

throat plate provided with feed-slots for passage of the usual feed-dog 5 and with the needle aperture 6 for passage of the needle 7 clamped to the needle-bar 2 and co-operating with a lower stitch-forming instrument, as for instance 5 a loop-taker moving in the circular path 7² below the work. 8 denotes the feed rock shaft of the usual under feeding mechanism for imparting four-motion movements to the feed-dog 5, which receives rising and falling movements 10 from the feed-lift rock-shaft 8'.

The presser foot 9 is secured to the lower end of the presser-bar 3 and carries a channeling knife blade 10 located immediately in front of the needle 7 viewed in the direction of feed and 15 adapted to cut an inverted T-shaped channel 11 in the leather ply 12 of a footwear sole having also a felt ply 13 to be stitched to the leather 20 ply 12 by stitches laid in the channel 11 so formed.

In the stitching operation the felt ply 13, being undermost, is engaged by the feed-dog 5, whereby the sole is fed beneath the needle.

14 denotes an upper feeding element constituted by a feed-slide located beneath and carried by the presser foot 9, being attached at its rear end to a carrier member 15 slidable on a guide bar 16 fitted to and extending rearwardly of the presser foot 9, whereby the feed-slide 25 is confined to horizontal reciprocatory movements.

As shown, the feed-slide 14 is formed with a central cut-away 17 to clear the needle 7 and the channeling knife 10.

The presser foot 9 bears on the feed-slide 14 through the medium of ball bearings 18 accommodated in a raceway 19 formed in the under-side of the presser foot and extending parallel to the line of feed.

The feed slide actuating mechanism comprises a short link 20 pivotally connected at one end at 21 to the carrier member 15 and pivotally connected at the other end at 22 to an arm 23 secured on one end of a horizontal rock shaft 24 journalled in a bracket 25 rising from the bed-plate 26 of the machine. On its opposite end the rock shaft 24 carries an arm 27 the bifurcated lower end 28 of which is operatively engaged by a roller 29 adjustably mounted in an arm 30 secured on the feed rock shaft 8 and projecting upwardly through a slot 31 in the machine bed-plate 26.

In operation, the feed-dog 5, the feed-slide 14, and the work 12, 13 advance together, the ball 55 bearings 18 permitting the feed-slide 14 to move forwardly with minimum frictional resistance, the feed-slide 14 sliding over the work in its return movement.

The channeling knife 10 is constituted by an 60

arcuate metallic blade, of approximately isosceles triangular shape in radial section, disposed in a vertical plane parallel to the line of feed, the apex of the triangle formed by a radial section of the 5 blade projecting forwardly or opposite to the direction of feed, and being located at the concave front edge of the blade. The lower end portion of the blade is shaped to present two lateral cutting edges 32 disposed in a horizontal 10 plane and diverging in the direction of feed away from a front vertical cutting edge 33. The knife projects below the feed-slide 14 to an extent depending on the depth of the channel 11 to be cut in the leather ply 12, it being understood 15 that the cutting edges 32 and 33 will cut a channel 11 of inverted T-shape in cross section in the leather ply 12, said channel 11 being held open until the stitch is formed and closing automatically 20 when the work passes beyond the stitching point. Formed in the rear face of the knife blade is a peripheral groove 34 the lower portion of which defines the forward boundary of a needle aperture 25 in the presser foot 9 and which serves to guide the needle close to the work.

25 The knife blade is adjustably clamped to the presser foot 9 by means of a clamp element 36 forming part of the presser foot and defining therewith a knife-receiving socket 37. The clamp element 36 is secured to the presser foot by 30 means of a stud 38 penetrating the forward end of the presser foot and engaged by a nut 39 adjustable to permit adjustment, removal, and replacement of the knife blade. The clamp element 36 is also provided with a dowel pin 40 engageable with a socket 41 in the presser foot.

As will be understood, by slackening back the nut 39, the knife blade 10 may be adjusted circularly in its socket 37 whereby to vary, within narrow limits, the distance which the cutting edges 32 project below the feed-slide 14.

40 Due to the arcuate form of the blade 10 tangent to the needle-path there is no possibility of the upper portion of the blade being fouled by the needle clamp 7' in the descent of the needle 7.

45 42 denotes a work guide roller overhanging the throat plate 4.

We claim:—

1. In a sewing machine, in combination, a 50 presser-foot above the work, under feeding mechanism including a feed-dog engageable with the under side of the work beneath said presser-foot, and a work-engaging feed-element engageable with the upper side of the work, said feed-element being located beneath and carried by 55 and movable relative to said presser-foot and participating in the feeding movements of said feed-dog.

2. In a sewing machine, in combination, a 60 presser-foot above the work, under feeding mechanism including a feed-dog engageable with the under side of the work beneath said presser-foot, a work-engaging feed-slide located beneath said presser-foot, means for supporting and guiding said feed-slide by said presser-foot, and means 65 operatively connecting said feed-slide with said under feeding mechanism.

3. In a sewing machine, a presser-foot above 70 the work, under feeding mechanism including a feed rock-shaft and a four-motion feed-dog operatively connected to said rock-shaft and engageable with the under side of the work, an arm on said shaft, a feed-slide movable beneath said presser-foot and engageable with the upper side of the work, guiding means for said feed-slide 75 whereby said feed-slide is confined to reciproca-

tory movements parallel to the plane of the work, an upper rock-shaft, and depending arms on said upper rock-shaft, one of said depending arms being linked to said feed-slide, and the other depending arm being operatively connected with 5 said first mentioned arm.

4. In a sewing machine, in combination, a presser-foot above the work, under feeding mechanism including a feed-dog engageable with the under side of the work beneath said presser-foot, 10 a work-engaging feed-slide located beneath said presser-foot, means for supporting and guiding said feed-slide by said presser-foot, anti-friction bearing members interposed between said feed-slide and the under side of said presser-foot, 15 and means operatively connecting said feed-slide with said under feeding mechanism.

5. In a sewing machine, in combination, a presser-foot formed on its under side with a ball race, 20 balls received in said ball race, under feeding mechanism including a feed-dog engageable with the under side of the work beneath said presser-foot, and a work-engaging feed-slide engageable with the upper side of the work, said feed-slide being carried by said presser-foot in engagement 25 with said balls and participating in the feeding movements of said feed-dog.

6. In a machine for simultaneously channeling and stitching material, in combination, stitch-forming means including a reciprocatory needle, a 30 presser-foot engageable with the upper side of the work and having a needle aperture, mechanism for feeding the work to and past the needle, and a work-channeling knife blade of arcuate form mounted in said presser-foot in advance of the 35 needle and having an operative end shaped to form an inverted T-shaped channel in the work, the rear face of said blade being grooved to guide the needle close to the work.

7. In a machine for simultaneously channeling 40 and stitching material, in combination, a presser-foot engageable with the upper side of the work, a work-channeling knife blade of arcuate form mounted for vertical adjustment in said presser-foot and having an operative end shaped to form 45 an inverted T-shaped channel in the work, and mechanism for feeding the work to said blade.

8. In a machine for simultaneously channeling 50 and stitching material, in combination, stitch-forming means including a reciprocatory needle, a presser-foot engageable with the upper side of the work and having a needle aperture, mechanism for feeding the work to and past the needle, 55 and an arcuate work-channeling knife blade of triangular form in radial section mounted in said presser-foot in advance of the needle and having an operative end shaped to form an inverted T-shaped channel in the work, the rear face of said blade being grooved to guide the needle 60 close to the work.

9. The combination with stitch-forming mechanism including a reciprocatory needle, of a lower four-motion feed-element, an upper two-motion feed-element, a presser-foot exerting pressure at 65 all times on said two-motion feed-element during a sewing operation, and an upper channeling knife carried by said presser-foot and disposed closely in advance of said needle and having its operative lower end formed with vertical and horizontal 70 cutting edges arranged to cut and open an inverted T-shaped channel in the work for entry by said needle.
